UNITED STATES PATENT OFFICE.

EMIL J. NIELSEN, OF ROCKFORD, ILLINOIS, ASSIGNOR TO PHENOLIC PRODUCTS CORPORATION, OF ROCKFORD, ILLINOIS, A CORPORATION OF DELAWARE.

TOILET-SEAT COVER.

Application filed July 28, 1927. Serial No. 208,914.

This invention relates to an improved toilet seat cover.

The principal object of the invention is to provide a cover having a heel portion integral therewith for sturdy supporting of the cover, the heel portion being extending at such an angle with respect to the plane of the cover as to avoid any likelihood of moisture collecting in or on it in service, this being a particularly important feature in the case of public toilet equipments where the attendants are frequently careless in the slushing off of seats and covers with cleansing and disinfecting fluids.

15 The invention is illustrated in the accompanying drawing wherein—

Figure 1 is a plan view of my improved cover shown in connection with a toilet seat;

Fig. 2 is an enlarged sectional detail taken 20 on the line 2—2 of Fig. 1, looking in the direction of the arrows; and,

Fig. 3 is a similar sectional detail showing the cover raised.

The toilet seat 4 in connection with which 25 the cover 5 of my invention is illustrated is preferably of moulded phenolic condensation product, known as bakelite material, although of course the invention is not considered to be especially limited to seats and 30 covers made of this or any other particular material. The hinge arms 6 are suitably moulded integral with the seat 4 to receive the pintle 7 which is supported at opposite ends in posts 8 arranged to be fixed in the 35 usual manner on the bowl of a water closet. It has been common practice to provide hinge arms for the swingable mounting of the cover and I am also aware that covers have been provided with integral heel portions to have pivotal mounting on the pintle 40 with the seat. However, the difficulty arose that the heel portions, being entirely closed, were found to present pockets for the collection of moisture especially when the cover 45 was left raised after the slushing off of the seat and cover with cleansing and disinfecting fluids. This objection was most keenly realized in the case of public toilets where such equipment is frequently subject to 50 careless treatment.

According to my invention I have provided a heel portion 9 preferably formed integral with the cover proper and provided

with an opening 10 for the reception of the pintle 7. The cover, when moulded like the 55 seat of phenolic condensation product, is cored out as indicated at 11 for lightness and cheapness without necessarily sacrificing strength. The heel portion extends at an angle of approximately 45° with respect to 60 the plane of the cover, as clearly appears in Figs. 2 and 3, thus presenting a sloping top or outside face at 12 rounded as indicated at 13 at the junction with the top of the cover, and a similarly sloped under or inner face 14. 65 It will be apparent by observation of Figs. 2 and 3 that in the lower position there is absolutely no chance of moisture collecting at the heel portion as any moisture at this point will drain off onto the bowl. In the 70 raised position of the cover the heel portion is disposed at the same angle to the horizontal and any moisture getting onto the cover will drain down over the inside face 14 of the heel portion and onto the bowl. In 75 either event the cover will be left perfectly dry.

I claim:

1. The combination with a toilet seat for a water closet, having a hinge pintle for 80 swingably mounting the same, of a cover arranged to lie in a substantially horizontal position to cover the seat or to be raised off the seat to a substantially vertical position, said cover having a heel portion integral therewith extending inwardly behind the seat to receive the pintle in an opening 85 therein, and said heel portion extending at an angle of about 45° to the plane of the cover whereby the outside face of the heel portion lies at about 45° to the horizontal when the cover is lowered and the inside face lies at about the same angle to the horizontal when the cover is raised so that no pocket is left in either position of the 90 cover and any moisture getting onto the cover will drain off and leave the cover dry.

2. The combination with a toilet seat for a water closet, having a hinge pintle for 95 swingably mounting the same, of a cover arranged to lie in a substantially horizontal position to cover the seat or to be raised off the seat to a substantially vertical position, said cover having a heel portion integral therewith extending inwardly behind 100 the seat to receive the pintle in an opening 105

therein, and said heel portion making an obtuse angle with the body portion of the cover whereby the outside face of the heel portion is disposed in a median position 5 between a vertical and a horizontal position, when the cover is lowered, and the inside face also is disposed in a median position

when the cover is raised so that no pocket is left in either position of the cover and any moisture getting onto the cover will 10 drain off and leave the cover dry.

In witness of the foregoing I affix my signature.

EMIL J. NIELSEN.
